(57) **CLAIM**

We claim the ornamental design for a telephone handset, as shown and described.

DESCRIPTION

FIG. 1 is a front perspective view of a telephone handset of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is an enlarged view thereof showing a portion of FIG. 2.

The dotted broken lines depict portions of the telephone handset that form no part of the claim. The dash-dot-dash broken lines define the boundary of the claimed design and form no part of the claim.
